DISPLAY RAIL FOR BEDS

William M. Nowell and James F. Gillespie,
Raleigh, N. C.

Application July 2, 1938, Serial No. 217,237

2 Claims. (Cl. 5—287)

This invention relates to a short rail or display rail employed in connecting the head and foot pieces of wooden beds, the rail holding the head and foot pieces in upright positions while 5 on display.

An important object of the invention is to provide a device of this character embodying adjustable hooks or clamping members adapted to be moved into and out of operation by means of 10 a sliding actuating bar, thereby eliminating the usual threaded bolts or similar threaded clamps commonly used in display rail construction.

Another object of the invention is the provision of a device of this character which will 15 lock the clamps in their active or clamping positions to the end that the clamps or hooks can only be disconnected by movement of the actuating bar.

With the foregoing and other objects in view, 20 which will appear as the description proceeds, the invention resides in the combination and arrangement of parts and in the details of construction hereinafter described and claimed, it being understood that changes in the precise embodiment 25 of the invention herein described, may be made within the scope of what is claimed, without departing from the spirit of the invention.

Referring to the drawings:

Figure 1 is an elevational view of a display rail 30 constructed in accordance with the invention, the rail being secured to a head and foot piece.

Figure 2 is an elevational view of the display rail in its inactive position.

Figure 3 is a sectional view through the display 35 rail.

Figure 4 is an end elevational view thereof.

Figure 5 is a vertical sectional view through the display rail.

Figure 6 is a fragmental detail view of one of 40 the threaded hooks and means for connecting the hooks.

Figure 7 is a detail view of the hook end of one of the hooks.

Referring to the drawings in detail, the display 45 rail embodies a substantially rectangular frame indicated generally by the reference character 5.

The end bars 6 of the frame 5, have slots 7, through which the flattened portions 8 of the hooks 9 operate. These hooks 9 are formed at 50 the outer ends of the rods 10, the rods 10 having their inner ends threaded, as at 11. As shown, the rods 10 operate in parallel spaced relation with respect to each other, and are held in position by means of the guides 12 that are formed 55 of lengths of wire material, there being provided

one of such wire members twisted into close engagement with the threaded end of each rod, so that by rotating the rods, the rods will be threaded through the coiled portions of the guides 12 and adjusted to the desired lengths to meet various requirements. The slots 7 are formed with enlarged ends so that the rods may be moved thereto, and rotated, when it is desired to make an adjustment. The intermediate portion of each length of wire material is loosely coiled around 10 the adjacent rod through which the adjacent rod operates, and bears against the adjacent bar 11 of the operating mechanism to be hereinafter more fully described, providing a yieldable connection between the operating mechanism and 15 rods 10. The operating means employed in operating the rods 10, embodies an actuating bar 13 operating through slots formed in the upper and lower bars 14 and 15 respectively, there being provided a loop 16 formed at one end of the bar 13, for the reception of the forefinger of the operator, for operating the bar to release or position the display rail. The ends of the wires of which the guides 12 are formed are looped around the pivoted bars 17 of the operating 20 means, as at 18, thereby limiting pivotal movement of the bars 17. Extensions 19 are formed on the lower ends of the bars 17, which are extended through openings in the lower bar 15 of the frame, pivotally securing the bars 17 to the 25 frame. Links 20 connect the upper ends of the bars 17 to the actuating bar 13, and it will be obvious that when the links 20 are moved to their active positions, or to positions shown by 30 Figure 1 of the drawings, the rods 10 and hooks 35 9 formed integral therewith, will be held hooked to the head and foot piece of the bed with which the display rail is used, with the result that the device may only be removed by pulling the 40 actuating bar 13 breaking the links 20, with the result that as the rods 10 are connected with the bars 17, through the wire guides 12 the rods are forced outwardly, releasing the hooks and 45 allowing the display rail to be removed.

It will be obvious that when the display rail is positioned so that the hooks 9 thereof hook over the rail pins of the head and foot sections of a bed, as indicated at A in Figure 1 of the drawings, the end bars of the frame are drawn into close engagement with the bed sections supporting the head and foot sections in upright positions.

We claim:

1. A display rail for displaying beds, comprising 55 a frame having side rails and end rails, spaced.

parallel rods having hooks at their outer ends, movable through openings formed in the end rails of the frame and adapted to hook over the side rail pins of the head and foot sections of a bed, a coiled spring adjustably secured to each of said rods, said springs having guide loops through which the rods extend, loops formed at the inner ends of the coiled springs, pivoted bars extending through the latter loops, and means for operating the pivoted bars to move the hook members towards each other, whereby the sections of the bed are moved into engagement with the end rails of the frame.

2. A display rail for displaying beds, comprising a frame having side rails and end rails, spaced parallel rods having hooks at their outer ends, movable through openings formed in the end

rails of the frame and adapted to hook over the side rail pins of the head and foot sections of a bed, a coiled spring secured to each rod, guide loops formed intermediate the ends of each spring, the guide loops of the spring carried by one rod, adapted to accommodate the adjacent rod, operating means within the frame, said operating means embodying pivoted bars and means for moving the pivoted bars, the inner ends of said coiled springs being looped around said pivoted bars, and said operating means adapted to operate the rods to move them into and out of clamping relation with the side rail pins of the bed sections.

WILLIAM M. NOWELL. 15
JAMES F. GILLESPIE.
